UNITED STATES PATENT OFFICE.

JOSEF SCHIESSLER, OF BADEN, NEAR VIENNA, AUSTRIA-HUNGARY.

APPARATUS FOR THE PRODUCTION AND STRENGTHENING OF ELECTRICAL VIBRATIONS.

1,101,148.

Specification of Letters Patent. Patented June 23, 1914.

Application filed November 23, 1910. Serial No. 593,890.

To all whom it may concern:

Be it known that I, JOSEF SCHIESSLER, subject of the Emperor of Austria-Hungary, residing at Baden, near Vienna, Austria-Hungary, have invented certain new and useful Improvements in Apparatus for the Production and Strengthening of Electrical Vibrations, of which the following is a specification.

This invention relates to apparatus for the production of electrical oscillations of high frequency and has for its object to provide an apparatus of the kind mentioned, in which a luminous arc between electrodes, which regulates itself to equal tension, current intensity or resistance is used for the generation of electrical oscillations by means of a suitable rotating magnet system. The striking of the arc as well as the adjustment and regulation of the same to constant tension, current intensity or resistance as hereinbefore mentioned is performed by another system of magnets (hereinafter termed holding and regulating magnets) which are adjustable within wide limits and are connected up in series or in parallel or differentially with the arc. The holding magnets strike the arc and tend to maintain it at a definite length; at the same time they give the desired amount of tension to the resilient member on which the electrode or contact is mounted. These holding magnets must therefore be of some powerful construction. On the other hand the said holding magnets exert a powerful damping action upon all the oscillations, free and forced oscillations, of the resiliently mounted electrode and hence on the luminous arc. In the generator circuit therefore an undulating current of sinusoidal shape occurs which sets into oscillations an adjustable oscillation circuit coupled with the generator circuit in which continuous and nearly undamped oscillations are thereby produced.

As the electrodes are likely to be unduly heated, a suitable cooling of the same will occasionally prove necessary. Such cooling may be effected by suitably arranging the systems of rotating magnets so as to provide for uniform cooling or this may be obtained by locating the electrodes in a chimney, through which some cooling medium is flowing.

The accompanying drawings diagrammatically illustrate constructions or ar-

rangements of apparatus according to the invention.

Figure 1 illustrates a high frequency generator arrangement for wireless telegraphic or wireless telephonic purposes, comprising for example two luminous arcs, although, in actual practical construction, four or a multiple of four luminous arcs would be provided. Fig. 2 shows an arrangement for transmitting the vibrations of a generator circuit to transmitting antennæ. Fig. 3 is an arrangement whereby the cooling of the electrodes is performed by a suitable construction of the rotating magnet system, a second disk with appropriate holes being added.

In the arrangement shown in Fig. 1 there are two luminous arcs the electrodes 1, 2 and 3, 4 of which are made of metal capable of being magnetized, such for example as iron, or of alloys capable of being magnetized and are fixed to elastic or spring carriers 5, 6 and 7, 8 respectively, or are made in one piece therewith.

To enable the luminous arc to be struck and maintained the positive electrodes 1 and 3 are each provided with a crater 9 made of a metal or alloy that is difficult to fuse and each negative electrode 2 and 4 is provided with a cone 10 of material of a like nature. Both parts 9 and 10, which will be hereinafter termed "contacts," may be made interchangeable and may be made of a radio-active metal, such as uranium and the like, or of an alloy possessing the same property, for the purpose of ionizing the gap between the electrodes. In some cases the positive contact alone may be made of a radio-active metal.

The two luminous arcs are connected in series in a circuit to which continuous current is supplied through the terminals 11 and 12. The positive terminal 11 is connected by conductor 13 to the connecting terminal 17 of the positive electrode 1 of one of the luminous arcs, through a self induction coil 14 provided with a closed subdivided iron core and through the windings of two electromagnets 15 and 16. The connecting terminal 18 of the negative electrode 2 of this luminous arc is connected to the connecting terminal 22 of the positive electrode 3 of the second luminous arc, through the windings of two electromagnets 20 and 21. The connecting terminal 23 of the elec-

trode 4 of this second luminous arc is connected to the negative terminal 12 by a conductor 24, through a self induction coil 25 also provided with a closed subdivided iron core. The subdivision of the closed iron cores of the coils 14 and 25 is in each case considerable.

A shunt 26 of the circuit just described includes the windings of regulating electromagnets 27, 28 corresponding to each of the luminous arcs respectively. The pairs of electrodes 1, 2 and 3, 4 which form the luminous arcs and the other luminous arcs which in practice are connected in series therewith and of which for practical purposes there are four or a multiple of four, are arranged in a circular row around a disk 29 formed of aluminium or similar material and mounted rigidly upon a shaft 30 that is rotated by a high-speed motor. Arranged at equal distances from each other upon the periphery of the disk 29 are magnetized steel pins or screws 31, the suitably proportioned heads of which act simultaneously upon the inner electrodes 1, 4 of all the luminous arcs when the disk rotates and whereby the lengths of the luminous arcs are periodically varied.

The cores of the holding electromagnets 15, 16 and 20, 21, which as hereinbefore stated are connected in series and are adjustable if necessary, are situated opposite the corresponding electrodes 1, 2, 3 and 4 and they tend to keep the springs 5, 6 and 7, 8 which carry them parallel to each other. When no current is passing through the coils of the magnets 15, 16, 20 and 21 the electrodes 1, 2 and 3, 4 are in contact with each other. The regulating electromagnets 27, 28 which, as hereinbefore stated are included in a shunt circuit and may likewise be adjustable if necessary, act upon the outer electrodes 2, 3 of each luminous arc and are so arranged that their axes lie in the direction of the luminous arc or in lines drawn through the corresponding contacts 9 and 10.

The holding magnets 15, 16, 20, 21 and the regulating magnets 27, 28 may in some constructions be without cores, that is to say may be constructed as solenoids, particularly in cases where magnetic hysteresis has a disturbing effect. The regulating magnets 27, 28 may either be connected in any suitable manner, for instance in series as shown in shunt or differentially, that is to say some of them be connected up in series and the rest in shunt.

The rotating magnet system may be conveniently provided with two aluminium disks 29 and 29', Fig. 3, which may be arranged a slight distance one above the other, the lower one being formed with holes 29^a through which the air flows from below and is driven radially outwardly from between the disks by centrifugal force.

A long distance electric transmission system may be directly connected in any suitable manner to a vibration generator constructed as described, or, for the purpose of wireless transmission, there may be connected thereto an antennæ system with an interposed vibration circuit consisting of an adjustable self induction coil and variable capacity device; the interposition of a vibration circuit being also of advantage in the connection of long distance transmission systems.

In the vibration arrangement shown in Fig. 2 the conductor 19 of the vibration generator is inductively connected by means of a transformer 33, to a closed vibration circuit 34 which includes an adjustable condenser constituting the capacity device 35 by charging and discharging which the said circuit is set in independent vibration. In the example under notice these independent vibrations are transmitted by inductive, that is to say magnetic, connection to an air conductor system 37. In this arrangement hereinafter described, the primary and secondary circuits may be connected by the condenser shown in my application Serial No. 738,304.

The action of the arrangement described is as follows: As soon as current is sent into the transmitting circuit at the terminals 11 and 12, Fig. 1, the two elastically mounted electrodes of each luminous arc will be moved the necessary distance apart to strike the arc, by the holding magnets 15, 16, 20, 21. As both elastic electrodes are touching one another when at rest, the circuit of current entering at the terminals 11 and 12 is closed, and therefore the current can pass through the windings of the holding magnets 15, 16, 20, 21. These magnets, when energized, attract their armatures 1 and 2 respectively, which form the electrodes of the system, thereby removing said electrodes from each other so that the arc is struck between them. At the same time the regulating magnets 27 and 28, connected in shunt, are energized and maintain the length and tension of the arc at a practically constant value which, if any disturbance occurs, is restricted by means of the arrangement described which is self-regulating. The said system is now influenced periodically by means of the rotating magnet system 29, 31, as soon as this system is set into operation after the arc has been struck. As soon as the magnets constituted by the magnetized steel screws 31 are brought opposite the inner electrodes 1, 4 these electrodes are attracted, so that the length of the luminous arcs and consequently also the difference of tension between the pairs of electrodes increases. The elements 5, 7, 15 and 21 coöperate with the magnets 27, 28, placed in shunt to restore the elastic electrodes to their original position,

thereby restoring the original length of the arc and the tension of the same. Every time a magnet 31 goes past a pair of electrodes this change of tension is repeated in a regular manner. The holding magnets insure a constant normal length of the luminous arcs and a constant difference of tension between the pairs of electrodes. The coils of the holding magnets simultaneously act as interposed quieting resistances and are either accurately compensated when made or are combined with a regulating reducing resistance which enables accurate adjustment to normal conditions to be made. The number of the fluctuations of the tension in the transmitting circuit depends on the number of the magnets 31 of the rotating system and on the speed at which the latter is driven by the high speed electric motor. When the number of magnets is constant this speed can be regulated within wide limits by means of a reducing rheostat. The intensity of the vibration energy produced by the vibration generator can be increased by increasing the number of luminous arcs arranged in the circuit. In like manner the fluctuation of the tension can be increased by placing the revolving magnets closer to the inner elastically mounted electrodes 1, 4 and by increasing the mass of the revolving magnets. The holding magnets 15, 16, 20, 21 cooperate with the regulating magnets 27 and 28, and attract the electrodes moved out of their positions by the magnetic pins of the disk, thereby restoring the normal length and the normal tension of the arc. This result will occur the sooner the stronger the attractive force of the electromagnets 15, 16, 20, 21 is made by suitable construction of the same. The function of said electromagnets is therefore to damp the electrodes which are oscillating with decreasing amplitude, very strongly, so that, instead of a periodic, an almost aperiodic oscillation takes place. Of course, thereby also the length of the arc and its tension is subjected to nearly aperiodic variations, whereby strongly damped current impulses occur in the primary circuit, which set up very weakly damped oscillations of high frequency in the secondary circuit.

I claim:

1. In apparatus for the production of electrical oscillations, a generator comprising means to produce a luminous arc, means to automatically regulate said arc to a normal tension, a normal strength of current or resistance and magnetic means to periodically and regularly vary the length and consequently the tension of said arc.

2. In apparatus such as described, a generator comprising arc forming electrodes,

magnetic means to automatically regulate said arc and controlled by current supplied to said electrodes and magnetic means to regularly and periodically vary the length and consequently the tension of said arc by varying the distance between the electrodes.

3. In apparatus such as described, a generator comprising yieldingly supported arc forming electrodes, electro-magnetic means to hold the electrodes apart during the passage of current between them, electro-magnetic means to regulate the length of said arc and magnetic means to periodically and regularly vary the length and consequently the tension of said arc.

4. In apparatus such as described, a generator comprising arc forming electrodes, yielding supports for the electrodes, electro-magnetic means acting on the yielding supports and electrodes to hold said electrodes apart and in series with the electrodes, and electro-magnetic means in shunt with and acting on one of the electrodes to control the length of the arc.

5. In apparatus such as described, a generator comprising yieldingly mounted metallic electrodes melting at high temperature, means to form and means to regulate the length of arc formed between the electrodes, and means to periodically and regularly vary the length of arc.

6. In apparatus such as described, a generator including coöperating electrodes one of which has an active element comprising a crater and the other has an active element comprising a cone, one of said elements constituted of radio-active metal for the purpose of ionizing the gases in the gap between them.

7. In apparatus such as described, a generator including coöperating electrodes one of which has an active element comprising a crater and the other has an active element comprising a cone, both of said elements constituted of radio-active metal for the purpose of ionizing the gases in the gap between them.

8. In apparatus such as described, a generator comprising yieldingly mounted electrodes, electro-magnetic means acting on the electrodes to form an arc between them, electro-magnetic means to control the length of arc, a rotating magnetic system adjacent one of the electrodes to periodically vary the tension between the electrodes, and means to control the speed of rotation of the system.

In testimony whereof I have hereunto set my hand in presence of two subscribing witnesses.
